UNITED STATES PATENT OFFICE.

SADAGIRO KAWANISHI, OF TOKYO, JAPAN.

DISINFECTING APPARATUS.

1,309,859.

Specification of Letters Patent. Patented July 15, 1919.

Application filed May 8, 1918. Serial No. 233,269.

To all whom it may concern:

Be it known that I, SADAGIRO KAWANISHI, a subject of the Emperor of Japan, and a resident of No. 117 Shimo-Shibuya, Shibuya-Machi, Toyotama-Gun, Tokyo, Empire of Japan, have invented new and useful Improvements in Disinfecting Apparatus, of which the following is a specification.

This invention relates to improvements in disinfecting apparatus and has for its object the destruction of the micro-organisms in books, paper currency, and other like articles.

In order that this invention may be clearly understood and more easily carried into practice, reference may be had to the accompanying sheet of drawing upon which is shown in somewhat conventional form an apparatus according to the invention partly in elevation and partly in vertical section.

Referring to the drawing, the numeral 1 designates a tank in which fumigating gas is contained, 2 the casing to receive the article to be disinfected, and 3 the pump interposed between the tank and casing, it being understood however that the construction of the tank and casing may be varied as desired.

G and G', respectively, represent vacuum and pressure gages, mounted upon the casing and tank, respectively. Preferably the casing 2 is internally provided with a plurality of superimposed shelves 8, which are here shown as rotatably mounted upon the central shaft A. The casing is also fitted at front with a sliding door, not shown.

The pump 3 is connected at suitable points with the casing 2 by an air extracting pipe 4 and a gas inlet pipe 5. The tank 1 is connected with the pump by a gas supply pipe 6 and a gas return pipe 7. 8 and 9, respectively, are discharge and feed pipes, the latter leading to another tank, not shown, from which fumigating gas may be supplied to the tank 1, a suitable cock to govern the flow of the air and gas being mounted upon each pipe, as at 10. At 11 and 12 are represented suction and discharge valves, respectively.

It will be understood that by operating the pump 3 after closing all cocks except the one mounted upon the air extracting pipe 4 and the gas return pipe 9 the air is exhausted to approximately a vacuum condition from the casing 2. By operating the pump 3

after closing all cocks except the one mounted upon the gas inlet pipe 5 and gas supply pipe 6 the fumigating gas is forced from the tank 1 into the casing 2 and into the molecular cavities of the articles, books or the like in the casing 2, thereby killing all infectious micro-organisms and without in any way injuring such articles. By operating the pump after closing all cocks except the one mounted upon the gas return pipe 7 and the gas feed pipe 9 the fresh supply of gas may be supplemented from the main tank into the tank 1. By operating the pump after closing all cocks except the one mounted upon the air extracting pipe 4 and the gas return pipe 7 the gas is enabled to be returned from the casing 2 into the tank 1.

In some instances, according to the nature of the micro-organisms, it may be desirable to incubate the bacteria before they are subjected to the sterilizing operation. To this end the casing 2 may take the form of a jacketed cylinder having peripherally inclosed space 13 adapted to receive therein steam or other suitable heating media at an appropriate temperature.

When it is desired to free the article treated from the smell imparted to it by the fumigating gas a suitable deodorizing agent or flavor may be admitted into the casing. This can be done by operating the pump after closing all the valves except the one mounted upon the gas feed pipe 9 and gas inlet pipe 5.

Having thus described my invention what I claim is:

1. In apparatus of the class described, the combination of a casing, a service tank to contain a gas, a pump, and connections between the said tank and the pump, said connections having cut off valves and also having controlling valves whereby the pump may be used to exhaust air from the casing and to force gas from the tank into the casing.

2. In apparatus of the class described, the combination of a casing, a service tank to contain a gas, a pump, and connections between the said tank and the pump, said connections having cut off valves and also having controlling valves whereby the pump may be used to exhaust air from the casing, to compress gas in the tank, and also to force gas from the tank and compress the same in the casing.

3. In apparatus of the class described, the combination of a casing, a service tank to contain a gas, a pump, and connections between the said tank and the pump, said connections having cut off valves and also having controlling valves whereby the pump may be used to exhaust air from the casing, to compress gas in the tank, also to force gas from the tank into the casing and compress

the same in the casing, and also to charge the service tank.

In testimony whereof I affix my signature in presence of two witnesses.

SADAGIRO KAWANISHI.
